P. J. HORGAN,
FASTENER SETTING MACHINE,
APPLICATION FILED SEPT. 16, 1918;

1,337,229.

Patented Apr. 20, 1920.

UNITED STATES PATENT OFFICE.

PATRICK J. HORGAN, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

1,337,229.

Specification of Letters Patent. Patented Apr. 20, 1920.

Application filed September 16, 1918. Serial No. 254,238.

To all whom it may concern:

Be it known that I, PATRICK J. HORGAN, a citizen of the United States, residing at Beverly, in the county of Essex and State of Massachusetts, have invented certain Improvements in Fastener-Setting Machines, of which the following description, in connection with the accompanying drawings, is a specification, like reference characters 10 on the drawings indicating like parts in the several figures.

This invention relates to fastener setting machines and will be herein shown and described by way of example in connection 15 with an eyeleting machine.

In most eyeleting machines the eyelets are delivered to an eyelet-inserting tool by a raceway which is reciprocated automatically so as to move the delivery end to and from a 20 delivering position in registration with the inserting tool. It is obvious, therefore, that the raceway must be retracted from the path of inserting movement of the tool during the stroke of the tool toward the work. In 25 some machines wherein the inserting tool is utilized to feed the work the retractive movement of the raceway follow lines substantially transverse to the lines of the feeding movement, but in machines of other 30 types, for example that shown and described in Letters Patent of the United States No. 934,066, granted September 14, 1909 upon application of George Goddu, the organization is such that the delivering and retractive movements of the raceway-end must 35 follow the path of feeding movement of the feeding tool. Under the latter conditions the retractive movement of the raceway must be of sufficient amplitude to provide 40 clearance for the tool with respect, not only to its inserting movement, but to its feeding movement, which amplitude is, of course, dependent upon the maximum length 45 of feeding movement, and consequently if the feeding mechanism is altered so as to diminish the length of the feeding steps the retractive movement of the raceway could, advantageously, be diminished accordingly, but so far as I am aware this has never been 50 done. The excess movement on the part of the raceway and its operating mechanism sets up unnecessary vibration in the machine as a whole and causes unnecessary wear of the operating mechanism.

55 Accordingly an object of the present in-

vention is to provide improved raceway-operating mechanism adapted to be regulated with regard to the amplitude of delivering and retractive motion imparted to the raceway consistently with the length of 60 feeding movement for which the work-feeding mechanism is adjusted, to the end that all unnecessary vibration and wear may be obviated.

Another object of the invention is to provide raceway-operating mechanism controlled by the work-feeding mechanism so that the extent to which the delivery end of the raceway is retracted to clear the inserting tool will, in every case, be determined by 70 the same adjustment that determines the length of the work-feeding movement.

Still another object of the invention is to provide mechanism constructed and arranged to operate the feeding tool and the 75 raceway collectively in such manner that the feeding movement of the one and the clearing motion of the other will be imparted by a reciprocatory actuator common to both.

Features of the invention will become apparent upon a consideration of the following specification describing the preferred embodiment of the invention and referring to the accompanying drawings, in which—

Figure 1 is a top view, partly in section, 85 of the parts of an eyeleting machine embodying my invention, and

Figs. 2 and 3 are fragmentary views showing these parts in successive operative positions.

Reference may be had to the above-mentioned Goddu patent for a description of the parts of the machine not herein fully shown and described. In general, however, it will be understood that the machine embodies a driving shaft 10 provided with a series of cams 12, 14 and 16, this shaft being mounted in a framework 18. Punching and setting tools 20 and 22 are carried in a movable head 24 pivotally mounted at 26 upon a bell crank lever 28 pivoted to the frame of the machine and controlled by the cam 14. By means of this cam controlled lever the head 24 is moved toward and away from the operator to bring the respective tools successively into operating position. Lateral feeding movement may be imparted to the setting tools by means of cam lever 30 controlled from the cam 12 and connected to the head 24 by means of links 32 and 34. 110

Adjustment of the extent of feeding movement is effected by movement of a control handle 36 pivoted upon the frame of the machine and adapted to be held 5 in any one of a plurality of positions by means of a pin 38 inserted in one of the holes of a quadrant 40. This lever 36 supports a link 42 acting as a fulcrum for the connecting point between the links 32 and 10 34, and, according to the position of the lever 36, more or less of the fixed movement of the cam operated lever 30 is transmitted to the tool carrying head 24.

Fasteners are supplied to the setting tools 15 from a hopper 50 through raceways 52, 54, this hopper being pivotally mounted upon a bracket 56 attached to the frame of the machine and movable about a point concentric with the hopper itself. Movement of 20 the tool carrying head 24 is transmitted to the raceways and incidentally the hopper by means of an arm 58 attached thereto and connected by links 60 and 62 to the tool carrying head. When these links are maintained 25 in alinement, it will be apparent that the movement of the tool carrying head is imparted directly to the raceways. The connection between said head and the raceways may, however, be altered and for this 30 purpose a link 64 is arranged to connect links 60, 62 with a bell crank lever 66, which is operable by the cam 16. When the link 64 is drawn backward as shown by Fig. 2 the effective length of links 60, 62 is shortened 35 so that the end of the raceway takes its delivering position relatively to the eyelet-inserting tool. When the latter has impaled an eyelet the cam 16 will straighten the links 60, 62 to impart the first stage of retractive 40 movement to the raceway.

In operation, then, the punches will be depressed in the usual manner to perforate the work, and the tool carrying head will then be retracted by the lever 28 to shift the 45 inserting tools into alinement with the previously punched holes. At this stage the ends of the raceways will be shifted into alinement with the inserting tools, as shown in Fig. 2. As soon, however, as the eyelets 50 have been impaled by the inserting tools the cam 16 will impart the first stage of retractive movement to the raceways, thereby shifting the delivery ends to the position 55 shown in Fig. 3. Inasmuch as the rest of the retractive movement of the raceways is always commensurate with and determined by the extent of feeding movement imparted to the tool carrying head, it will never be excessive even when the feeding mechanism is 60 set for the minimum stroke.

Having thus described my invention, what I claim as new and desire to secure Letters Patent of the United States is:

1. In a fastener-setting machine, work- 65 feeding means including a fastener-insert-

ing and work-feeding tool, means for varying the amplitude of feeding movement imparted by the feeding means, a raceway the delivery end of which is movable in one direction to carry a fastener to delivering 70 position and in the opposite direction to clear the tool, and mechanism controlled by the work-feeding means for reciprocating the delivery end in said directions with an amplitude of movement determined by that 75 of the work-feeding movement.

2. In a fastener-setting machine, work-feeding means including a fastener-inserting and work-feeding tool, a raceway the delivery end of which is movable relatively to 80 said tool to deliver fasteners thereto, and raceway-operating means controlled by the work-feeding means for moving the delivery end in opposite directions to and from delivering position. 85

3. In a fastener setting machine, a setting tool, a carrier therefor movable laterally to effect feeding of the work, means for adjusting the extent of feeding movement imparted to the carrier, a raceway for supplying 90 fasteners to the setting tool, and means for moving the raceway to and from fastener delivering position with a stroke the amplitude of which is determined by the adjustment of the feeding mechanism. 95

4. In a fastener setting machine, a fastener presenting tool, a movable carrier for said tool constructed and arranged to feed the work, adjustable means for effecting a lateral movement of the carrier, a raceway 100 for supplying fasteners to the tool, said raceway being mounted for movement toward and away from the tool, and means connecting the carrier for the tool and the raceway for displacing the raceway when the work 105 is fed, said means being constructed and arranged to alter the movement of the raceway by an amount proportional to the variation in the extent of feeding movement imparted to the carrier. 110

5. In a fastener setting machine, a fastener presenting tool, a carrier therefor movably mounted to permit lateral movement thereof to feed the work, a raceway for supplying fasteners to the tool, said raceway being mounted for lateral movement toward and away from the carrier, connecting means between the carrier and the raceway constructed and arranged to impart the movement of the carrier to the raceway, and means for altering said connecting means to effect a movement of the raceway into delivering position with respect to the fastener presenting tool. 115

6. In a fastener setting machine, a fastener presenting tool, a carrier therefor pivotally mounted to permit lateral feeding movement of the carrier, a pivotally mounted raceway for supplying fasteners to the tool, means for connecting said carrier to said 120 125 130

- raceway comprising toggle links, and cam operated means for controlling said toggle constructed and arranged to bring the raceway into fastener delivering position and to displace laterally the raceway with the carrier during the lateral feeding movements thereof.
7. In a fastener-setting machine, fastener-inserting and work-feeding mechanism including a fastener-inserting and work-feeding tool, a raceway the delivery end of which is movable to and from delivering position along the feed-path of the tool, and means controllably related to the work-feeding mechanism for moving the raceway to and from delivering position with an amplitude of movement determined by that of the work-feeding movement.
8. In a fastener-setting machine, a fastener-inserting and work-feeding tool, a raceway the delivery end of which is movable along the feed-path of said tool to deliver fasteners and to clear the tool, and mechanism arranged to operate said tool and the raceway collectively, the one to feed the work and the other to maintain tool-clearance.
9. In a fastener-setting machine, a fastener-inserting and work-feeding tool, a raceway the delivery end of which is movable along the feed-path of said tool, and mechanism arranged to move the delivery end along said path to and from delivering position, and thereafter to move the delivery end and the tool in unison to feed the work.

In testimony whereof I have signed my name to this specification.

PATRICK J. HORGAN.
